FRUIT PEELER OR THE LIKE

Samuel J. Popeil, 2920 N. Commonwealth,
Chicago, Ill. 60657

Filed Mar. 7, 1966, Ser. No. 1,304

Term of patent 14 years

(Cl. D89—1)

FIG. 1 is a perspective view of a fruit peeler or the like showing my new design;

FIG. 2 is a front elevational view thereof;

FIG. 3 is an elevational view taken on line 3—3 of FIG. 2;

FIG. 4 is an elevational view taken on line 4—4 of FIG. 1; and

FIG. 5 is a perspective view taken from the side opposite that in FIG. 1 and with the article inverted.

I claim:

The ornamental design for a fruit peeler or the like, substantially as shown.
